UNITED STATES PATENT OFFICE.

HERMAN BUCHHOLZ AND WILLIAM MORRIS, OF JANEVILLE, WISCONSIN.

CARRIAGE-TOP.

SPECIFICATION forming part of Letters Patent No. 297,968, dated May 6, 1884.

Application filed December 20, 1883. (No model.)

To all whom it may concern:

Be it known that we, HERMAN BUCHHOLZ and WILLIAM MORRIS, of Janesville, in the county of Rock and State of Wisconsin, have 5 invented certain new and useful Improvements in Carriage-Tops; and we do hereby declare the following to be a full, clear, and exact description of the invention, such as will enable others skilled in the art to which it appertains to make and use the same.

Our invention relates to an improvement in carriage-tops, the object of the same being to provide the carriage-top with a forward extension, whereby we are enabled to dispense 15 with one or more bows, thereby considerably lessening the cost of manufacture, and enabling the remaining bows to be set back far enough so as not to interfere with a person while entering or leaving the vehicle.

20 A further object is to provide a forward extension to a carriage-top which is adapted when the top is in its folded adjustment to partially overlap and protect the interior of the same from dust, &c.; and with these ends in 25 view our invention consists in certain details of construction and combinations of parts, as will be hereinafter described, and pointed out in the claims.

30 In the accompanying drawings, Figure 1 is a view in elevation showing our improvement in its open adjustment. Fig. 2 is a view thereof, with the dotted lines showing it in its half-open adjustment and the full lines in its closed adjustment; and Fig. 3 is a modification of our 35 improvement.

A, B, and C represent the bows of a carriage-top suitably attached to the frame or body of the carriage, and adapted to support the front, center, and rear thereof, respectively. The bows A and C are provided with 40 pivot-holes, through which pass pivots F and G, which secure in position the top-brace H, which is likewise provided with holes for the reception of the pivots F and G. The top-props I are pivotally secured to the frame J of the carriage, having their upper ends pivotally secured to the bows A, and are provided with an upwardly-closing joint, K. The end bows, A and C, are each pivotally attached, near their upper ends, to the top-brace 45 H, which latter is provided centrally between

the end bows with a downwardly-closing knuckle-joint, L, and forward of the bow A with an upwardly-closing knuckle-joint, M. This articulated rod is for the purpose of holding the bows separated and the leather or other covering taut, while the top-prop I is adapted to perform the ordinary function of holding the bows in upright position. The top-braces H are each provided in front of 50 the front bow with the bow N, which is rigidly secured thereto by the rigid joint O. Thus it will be seen that when the bows are held in an upright position and the top-brace straightened out, the bows are held apart, and 55 the leather covering, which is secured to the front bows and the curved horizontal bow N, the outer ends of which are rigidly secured to the outer ends of the part O of the top-brace, is drawn perfectly taut, and so held in position. 60 It will be also seen that when it is desired to incline the top, the top-prop I is displaced from its fixed position by means of the knuckle-joint K, and the top-brace H likewise folded by means of the knuckle-joints M and L, thus 65 permitting the top to fall backward; and by means of the upwardly-acting knuckle-joint M the extension N drops down and partially overlaps and covers the interior of the top. 70

Instead of placing the bow of the extension 80 in the same horizontal plane with the top-brace, we may place the said bow in a plane at an angle with the plane of the brace, as shown by the modification in Fig. 3 of the drawings. By this construction the view from the interior 85 of the carriage will be unobstructed.

Having fully described our invention, what we claim as new, and desire to secure by Letters Patent, is—

1. In a folding carriage-top, the combination, with the bows, of the top-brace pivotally secured to the front and rear bows, and having knuckle-joints at either side of its front pivot, a forwardly-extending curved bow rigidly secured to the front ends of the top-brace, 95 and the cover secured to the bows and the forward extension, substantially as and for the purpose set forth.

2. In a folding carriage-top, the combination, with the bows, of a jointed brace pivotally secured to the front and rear bows, and a top-prop pivotally secured to the carriage. 100

frame, with its upper end pivotally secured to the front bow at the juncture where the brace is secured, substantially as and for the purpose set forth.

5. In a folding carriage-top, the combination, with the bows, of a top-brace secured to the front and rear bows, and provided with upwardly and downwardly working knuckle-joints, and a top-prop secured to the carriage-frame and front bow, and provided with an

upwardly working knuckle-joint, substantially as and for the purpose set forth. In testimony whereof we have signed this specification in the presence of two subscribing witnesses.

HERMAN BUCHHOLZ.

WILLIAM MORRIS.
